[57] CLAIM

The ornamental design for telephone set, as shown and described.

DESCRIPTION

FIG. 1 is a front elevational view of telephone set showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front, bottom, and right side perspective view thereof with the handset exploded from the base;

FIG. 8 is a front, bottom, and left side perspective view thereof with the handset exploded from the base;

FIG. 9 is a front elevational view of a second embodiment of my new design of FIGS. 1-8;

FIG. 10 is a right side elevational view thereof;

FIG. 11 is a left side elevational view thereof;

FIG. 12 is a top plan view thereof;

FIG. 13 is a bottom plan view thereof;

FIG. 14 is a rear elevational view thereof;

FIG. 15 is a front, bottom, and right side perspective view thereof with the handset exploded from the base;

FIG. 16 is a front, bottom, and left side perspective view thereof with the handset exploded from the base;

FIG. 17 is a front elevational view of a third embodiment of my new design of FIGS. 1-8;

FIG. 18 is a right side elevational view thereof;

FIG. 19 is a left side elevational view thereof;

FIG. 20 is a top plan view thereof;

FIG. 21 is a bottom plan view thereof;

FIG. 22 is a rear elevational view thereof;

FIG. 23 is a front, bottom, and right side perspective view thereof with the handset exploded from the base; and,

FIG. 24 is a front, bottom, and left side perspective view thereof with the handset exploded from the base.
